RIBBON SEPARATING DEVICE AND
METHOD

Anna Maria Louise Woell, Pompton Lakes, N. J.

Application July 24, 1948, Serial No. 40,563

6 Claims. (Cl. 26—70)

1

This application is a continuation-in-part of my copending application, Serial No. 647,532, filed February 14, 1946, now abandoned, for Band separating and classifying device.

This invention relates to a ribbon separating device and method and refers more particularly to an apparatus and method for separating strips of woven labels so that they may be inspected and counted.

It is customary in the manufacture of woven labels in strip form to merely collect the labels in a very large bag as they come off the weaving machine or loom in strip form, and in a representative instance, such a bag may contain 40 or 50 ribbons, each 20 yards long, and constituted of labels end to end, the ribbons being loosely jumbled in the bag. Before the labels are counted and packaged for shipping to the user, they must be individually inspected. It is customary for a group of operators to begin operations on a bag, each locating the end of a ribbon and proceeding therealong, inspecting each label. Such procedure however results in numerous interruptions due to the fact that the ribbons are tangled or that they become tangled in the process of inspection. The entire procedure of inspection is very tedious and comparatively costly.

An object of the present invention is to provide an apparatus and method of drawing out the label ribbons so that they lie adjacent and parallel and may be drawn past each other for inspection individually without becoming tangled.

A further object is to shorten the time required for inspection.

Still a further object is to provide an apparatus adapted to handle ribbons of varying lengths.

In accomplishing the objects of the present invention there is provided a pulley mounted on a surface at a considerable elevation above the head of the operator, preferably. A ring is suspended from the end of a string, the string being led over the pulley and the other end thereof being engageable by a hook which is located in some such object as a wall or an upright column at a convenient height. A substantially horizontal bar is mounted almost at floor height. When the ribbons to be inspected are long, the free ends of a plurality of the ribbons may be tied to the horizontal bar after having been led through the ring which has been lowered through the pulley to a convenient height. The string or cord may now be used to pull the ring to a greater height, which results in the ribbons being stretched out in a substantially parallel relation to each other until half their length extends upward from the bar

2

to the ring and the other half downward again to the free hanging end. Each ribbon may now be inspected without causing tangling with the others by freeing the end thereof from the bar and pulling the ribbon slowly through the hands of the operator, inspection taking place as the ribbon passes through the hands of the operator.

To inspect the ribbons of a shorter length, the ends of a multiplicity of ribbons are looped over 10 the ring and tied to themselves with the ring at a convenient height, and the ring then raised to a greater height to draw the ribbons out of the bag.

In the representative instance mentioned previously, 15 or more ribbons may be connected to each of three rings and raised simultaneously to completely evacuate one bag of 45 or 50 ribbons. The use of this method and apparatus has permitted inspection of a given number of label ribbons in approximately 10 percent of the time formerly devoted to that operation.

Other objects of this invention will in part be obvious and in part hereinafter pointed out. The invention accordingly consists in the features of construction, combinations of elements, and arrangements of parts which will be exemplified in the constructions and methods hereinafter described. In the accompanying drawing, in which is shown one of the various illustrative embodiments of this invention:

Figure 1 is a perspective view of the apparatus being used in the separation of a multiplicity of long ribbons, showing the ribbons in various states of separation.

Figure 2 shows shorter ribbons being separated.

Figure 3 is a fragmentary elevational view of a ribbon of labels it being understood that no such detailed showing as of the contents of the label is possible in Figures 1 and 2.

Referring now to Figure 1, a mass 10 of ribbons 22 is contained in a bag or a box not shown. The mass 10 usually comprises three parts, the parts A1, A2, A3, being constituted of a multiplicity, usually 20 to 30 of the ribbons 22. The parts A1, A2, A3 are defined by having one end of each of the ribbons 22 tied together in a bunch by a string, not shown. All parts A1, A2, A3, and more if there are any more, of the mass 10 are fastened between the clamp bars 11, 12 after being led through the rings 13, 14, 14A. The rings 13, 14, 14A are suspended from ropes 15, 16, 17, the ropes 15, 16, 17 being led over pulleys 18, 19, 20 mounted on a bracket 21 the latter being mounted on a ceiling or the like. The other end of the ropes 15, 16, 17 are engageable by the hooks 23

which are mounted on a wall, upright column, or the like.

In Figure 1, rings 14, 14A are shown lowered to a height convenient for the leading of the parts A2, A3, whereas ring 13 is shown pulled up to an elevated position, its rope 15 having its free end engaged on hook 23 to maintain ring 13 in the elevated position. It must be understood however that all the rings 13, 14, 14A, or as many of them as may be necessary to receive all of the parts A1, A2, A3, of a particular mass 10 of ribbons, should be at the same height at any given time. That is, the parts A1, A2, A3, should be led through the rings and fastened in the clamp bars 11, 12, and all of the rings which are in use in the particular operation raised to the elevated position of ring 13. In this way the ribbons are prevented from becoming tangled by the operation of drawing them out to their full length. Once all of the parts A1, A2, A3, are in the drawn out, elevated position of part A1 in Figure 1, the individual ribbons 22 of the parts may be separated consecutively from the parts by pulling downward on that portion of the ribbon extending from the clamp bar to the ring. Inspection of the ribbon may then proceed.

The above method and apparatus eliminates various objections to the previous method of inspecting the label ribbons. These disadvantages include the fact that if a single part of a single ribbon is attempted to be withdrawn from the mass 10, tangles and bunches develop in the mass 10 periodically and frequently, so that in a room full of operators engaged in the operation of inspection, one or more operators may have to leave their work to assist an operator who has reached a point on the ribbon which he is attempting to inspect where a ribbon is hopelessly snarled up with the rest of the ribbons.

Referring to Figure 2, the apparatus of Figure 1 is shown in connection with a mass 30 of ribbons 22 comprising the parts B1, B2, the ribbons comprised by the parts B1, B2, being shorter than ribbons 22 illustrated in Figures 1 and 3. In separating the ribbons of the parts B1, B2, one end of each part B1, B2 is connected to a ring 13A, 14B, both rings at the time of the connection of the parts B1, B2, thereto being in the lower position illustrated by the position of ring 14B. All of the parts of the mass 30 being connected to rings, the rings are simultaneously raised to the elevated position in which ring 13A is shown. The ribbons of a part are so fastened together that pulling upon the lower end of a single ribbon when the part is in the elevated position of ring 13 in Figure 2 will result in the ribbon coming free from the part, whereupon the ribbon may be inspected. This fastening may conveniently take the form of merely looping the short end of part B1 over ring 13A and tying it to the main course of part B1 by a separate piece of string B3. This method of separating the ribbons and parts also is free from the possibility of tangling or snarling the ribbons as experienced in former procedures.

It will thus be seen that there is provided a device in which the several objects of this invention are achieved, and which is well adapted to meet the conditions of practical use. As various possible embodiments might be made of the above invention and as various changes might be

made in the embodiments above set forth, it is to be understood that all matter herein set forth or shown in the accompanying drawing is to be interpreted as illustrative and not in a limiting sense.

What is claimed is:

1. In an apparatus for separating ribbons, stationary means for engaging one end of a multiplicity of said ribbons, a pulley mounted at a substantial distance above said means, a rope led over said pulley, a ring suspended from one end of said rope, and means for engaging the other end of said rope to maintain said ring in a given position.
  2. In an apparatus for separating ribbons, a clamp bar for engaging one end of a multiplicity of said ribbons, a pulley mounted at a substantial distance above said bar, a rope led over said pulley, a ring suspended from one end of said rope, and means for engaging the other end of said rope to maintain said ring in a given position.
  3. The method of separating woven label ribbons from a mass of ribbons comprising parts, each part comprising a multiplicity of ribbons fastened together by a string or the like uniting in parallel relation one end of each ribbon, comprising fastening an end of each part to a separate elevating means, simultaneously elevating all the parts and removing ribbons from the parts.
  4. The method of separating woven label ribbons from a mass of ribbons comprising parts, each part comprising a multiplicity of ribbons fastened together by a string or the like uniting in parallel relation one end of each ribbon, comprising fastening an end of each part to a separate elevating means, simultaneously elevating all the parts and removing the ribbons singly from the parts.
  5. The method of separating woven label ribbons from a mass of ribbons comprising parts, each part comprising a multiplicity of ribbons fastened together by a string or the like uniting in parallel relation one end of each ribbon, comprising leading each part through an elevating means, fastening said part to a stationary object, elevating said elevating means until said part is completely suspended by said elevating means, and removing each ribbon singly from its part.
  6. The method of separating woven label ribbons from a mass of ribbons comprising parts, each part comprising a multiplicity of ribbons fastened together by a string or the like uniting in parallel relation on one end of each ribbon, comprising leading each part through an elevating means, fastening said part to a stationary object, elevating said elevating means until said part is completely suspended by said elevating means and removing ribbons from said part.
